COMBINED APPOINTMENT CLOCK DIAL AND MEMO PAD HOLDER

Edward M. Rubin, Leominster, Mass., assignor to Commonwealth Plastics Corp., Leominster, Mass., a corporation of Massachusetts

Filed Mar. 6, 1961, Ser. No. 64,153

Term of patent 14 years

(Cl. D74—1)

FIG. 1 is a top plan view of a combined appointment clock dial and memo pad holder showing my new design;

FIG. 2 is an end view thereof as seen from the top of FIG. 1;

FIG. 3 is a cross sectional view thereof taken on line 3—3 of FIG. 1;

FIG. 4 is an edge view as seen from the right of FIG. 1, and

FIG. 5 is a sectional view taken on the line 5—5 of FIG. 1.

The broken line illustration of a pad and writing instrument is for illustrative purposes only.

I claim:

The ornamental design for a combined appointment clock dial and memo pad holder, substantially as shown and described.
